[57] **ABSTRACT**

This invention relates to a combined rotary and side detent switch.

The improvement resides in the combination of a slide having a plurality of spaced female contacts, with a rotary detent mechanism, a motion-transmitting means being provided between the slide and the rotary detent for conversion of the latter to a corresponding sliding movement of said slide and said motion transmission means being formed into a recess or groove-shaped female member slidably cooperating with a follower pin or rib-shaped male member formed on an extension of said slide.

FIG. 14

SLIDE SWITCH WITH ROTARY SPRING DETENT MECHANISM

This invention relates to a slide switch with a rotary spring detent mechanism.

The main object of the invention is to provide an unique combined rotary and slide detent switch, capable of obviating several conventional drawbacks inherent in the conventional slide switch and the rotary-type switch.

A further object is to provide an improved slide switch of the above kind, capable of providing multicontacts switching operation in an accurate and reliable way.

These and further objects, features and advantages of the invention will appear more apparent when read the following detailed description of the invention by reference to the accompanying drawings illustrative of several preferred embodiments of the invention.

In the drawings:

FIGS. 1 and 2 are a side view and a cross-sectional views of a comparative conventional slide switch, the cross section being taken substantially along a section line II-II and illustrated on somewhat enlarged scale.

FIG. 3 is substantially a longitudinally sectional view of a first embodiment of the invention.

FIGS. 4 and 5 are respective cross-sectional views taken along section lines IV-IV and V-V' shown in FIG. 3.

FIGS. 6 and 7 are perspective views of relatively cooperating constituents parts comprised in the first embodiment.

FIG. 8 is a partially broken-away plan view of cooperating slide end and cam member employed in the foregoing embodiment.

FIG. 9 is a partially broken-away perspective view of said cam member.

FIG. 10 is a substantially longitudinally sectional view of nearly a half of a second embodiment of the invention, said half being substantially corresponding to nearly a left half of the switch shown in FIG. 3.

FIG. 11 is an enlarged cross-sectional view of the second embodiment shown in FIG. 10, being taken substantially along a section line XI-XI.

FIG. 12 is a substantially similar view to FIG. 10, showing a main part of a third embodiment of the invention.

FIG. 13 is an enlarged cross-sectional view of the third embodiment, being taken substantially along a section line XIII-XIII shown in FIG. 12.

FIG. 14 is a plan view of the connecting parts between slide and cam member employed in the third embodiment.

As a preparatory description for clarifying the background technique of the invention, a comparative conventional detent slide switch combined with a slide switch element will now be illustrated by reference to FIGS. 1 and 2.

This rotatably operation slide switch comprises an elongated casing 1 having a channel-shaped cross section which is opened at its bottom side as seen. The opened lower side of the casing 1 is formed with two series of inwardly bent tabs 1a and 1b; said open casing bottom is, however, closed by a closure strip 3 which is made of an insulating material such as plastic and mounted on said tabs 1a and 1b and carries rigidly a number of stationary contacts 2, each thereof projecting into the inside space of the casing 1. The inwardly projecting ends of the stationary contacts 2 are denoted by 2a in common.

In the interior space 5 of the casing 1, a slide 6 is slidably mounted on the closure strip 3 which is formed integrally with an upwardly directing projection 8 projecting through an axially extending slot 7 formed through the upper wall part 1c of casing 1. The slide 6 is formed with one or more stepped recesses 6a in each of which a female spring contact 9 is mounted elastically in position. It will be clear that by operating the projection 8 as a manipulating element so as to move the slide 6 axially to and fro a successive single contact combination or a certain complex multicontact combination can be brought about, as the case may be, depending upon any selected one of the stop positions of the slide 6, for performing each stage a selected switching position in a "on-" or "off-" mode, or transfer mode, as occasion may desire.

It is, however, a modern desire, especially with high-class stereotuners, amplifiers, all wave radio receiver sets, to provide a chance of switching a plurality of circuits simultaneously. Another desire is naturally to provide a chance for performing the switching operation from the front panel side of the instrument from the point of design and/or ornamental demands. Since at the backside of the panel there are provided a large number of highly complicated instrumental constituents arranged in a highly crowded manner so that difficulties are frequently encountered to fit the aforementioned kind of switching slide at the rear side of the panel with avoidance of possible mechanical interference with neighboring instrumental constituents. In order to avoid such difficulties, it would be naturally conceivable to employ the conventional type of rotary switch having a contact disc. Since, however, such rotary-type switch is rather more voluminous and costly than the slide switch, the aforementioned drawback inherent in the slide switch can only be solved in rather rare events and only with much difficulties.

Next, referring to FIGS. 3-9, a preferred first embodiment of the present invention will be described in detail hereinbelow.

In this embodiment, numeral 10 represents a metallic casing having a channel cross section as before. This casing 10 is opened downwards; this open bottom is, however, closed by a closure strip 13 made of an insulating material as before which strip is fixedly attached to the casing 10 in the shown position by two series of inwardly bent-up opposing tabs 10a and 10b. A plurality of stationary male contacts 12 are arranged in one or more axial rows and at their regularly spaced mutual distances and mounted fixedly in the closure strip 13 by molding or other conventional fixing measure.

A slide 14 made of an insulating material is slidably received in the interior space 10c of the casing 10, said slide being formed in its bottom part with a plurality of recesses 15 arranged in one or more axial rows in registration with those of the stationary contacts 12. As seen, these recesses 15 are separated from each other at a predetermined mutual distance when seen along a specific row, each of these recesses being fitted with a female spring contact 16 so as to cooperate with a selected pair of the inwardly projecting ends 12a of stationary male contacts 12. Under occasions, certain of these projecting ends 12a may have a different widths.

The slide 14 is urged resiliently by a coil spring 17 so as to move axially in the left-hand direction when seen in FIG. 3, the right-hand end of said spring being kept in engagement with an inwardly directing hook 10e formed on the right-hand end wall 10d of casing 10.

A mounting member 18 is attached fixedly at the left-hand end extension walls 10f and 10g of the casing 10 by means of tabs 10g and 10h and mounts in turn rotatably a sleeve 22 which mounts fixedly an operating shaft 19 formed at its outer end with a knurled grip 19a. Thus, sleeve 22 and shaft 19 can rotate in unison with each other. To the inner end of shaft 19, a hollow cylindrical cam member 20 is fixedly attached which is formed, however, integrally with a detent disc part 20a. The cam member 20 is formed further on its inside cylindrical wall surface with a substantially triangular recess 30 having a straight edge 30a and a slightly curved edge 30b (especially cf. FIG. 8).

Slide 14 is formed with an axially extending reduced extension 14a which is formed in turn with a rib 21. This rib 21 is kept with its tip end 21a in contact with said slightly curved edge 30b. Under occasions, this rib 21 may be replaced by a pin, although not shown.

Detent disc part 20a is formed with integral projections 23 on its periphery, a recess 23a being thus formed between two neighboring projections 23. In the present specific embodiment, these projections 23 are provided four in their number, and the detent recesses 23a are three as shown.

A detent ball 27 is arranged to cooperate with any one of said recesses 23 and kept in rotatable engagement with an opening 26a perforated in a pressure spring strip 26, the end extremities of the latter being kept in pressure engagement

with respective receiving hooks 24 and 25 or other similar male or female catch means formed on or in casing extension walls 10^f and 10^f, respectively.

The operation of the first embodiment of the invention so far shown and described is as follows:

When an operator manipulates the shaft 19 through its grip end 19^a to rotate in either clockwise or counterclockwise direction, as the case may be, when seen in FIG. 4, the cylindrical cam member 20 is rotated to the same degree in the selected direction. In this way, the detent ball 27 will override one or more projections 23 and brought into engagement in selected one of the detent recesses 23^a. By the rotational movement of the cam member and with pressure engagement of tip end 21^a of rib 21 with the curved edge 30^b, the slide 14 will be shifted rightwards against the action of return spring 17, or leftwards under the action thereof, depending upon the rotational direction of the shaft 19.

The detent disc 20^a is formed on its outer surface with a segmental stopper member 29 made integral therewith, so as to limit the rotational range of the cam to about 90° or so, by occasional engagement with either of stopper projections 18^a and 18^b formed on the mounting member 18. The rotational angle so limited may be larger or smaller than the above specified value, as the case may be.

Since the design, number and arrangement of the detent recesses 23^a are so selected that for each of the thus selected detent position for the slide 14, one of several switching-off positions is provided for changing the cooperative mode between the male contacts 12 and the female contacts 16 as known.

In the foregoing embodiment, there are provided three female contacts 16. Each of these contacts 16 has a conventional shape and function. When one of these contacts 16 is sectioned along a section line Y-Y' in FIG. 3, then, it represents substantially a similar configuration as shown in FIG. 2.

Any one of these contacts 16 controls four male or stationary contacts 12^a, the number of these controllable male contacts by any one of said female contacts is defined by the number of said detent projections 23.

As an example, the left end positioned female contact 16 covers in its operation four male contacts 12 which have been, however, denoted "A" "B" "C" and "D" in succession from left to right. When the related female contact 16 is positioned, male contacts "A" and "B" are brought into electrical connection with each other. When the same female contact 16 is shifted a step rightwards by movement of the slide 14 in the same direction, next two contacts "B" and "C" are brought into electrical connection with each other. When the same female contact 16 is shifted a still further step again rightwards, further next two contacts "C" and "D" are brought into electrical connection each other.

Naturally, the switching mode is not limited to such specific

one, and may be conceivable in other various ways.

It will be seen that in the foregoing embodiment as well as several succeeding embodiments to be described, the switching slide is subjected to an accurate dividingly selected 5 positioning action derived from the detent ball-and-recess assembly so that the slide can be positioned in a highly accurate way at each selective multicontact switching position.

The second embodiment shown in FIGS. 10 and 11, the structure and operation are substantially similar to those of 10 the first embodiment. Therefore, similar parts of the present embodiment to those of the foregoing have been denoted by respective same reference numerals, yet each being attached with a prime for easier identification and comparison.

The only difference of the present embodiment from the 15 foregoing resides substantially in that the pressure spring strip 26' has been dispensed with the ball-receiving perforation as at 26^a shown in FIGS. 3 and 4 employed in the foregoing, and instead, the mounting member 18 is formed such perforation 18^a'. As will be easily seen that the ball-positioning effect can 20 be equally attained as before.

Finally, a third embodiment shown in FIGS. 12-14, substantial construction and function are similar to those of the first embodiment. A substantial difference resides in the provision of a pin-and-groove mechanism.

Therefore, similar parts are denoted with respective same 25 reference numerals, each being, however, added with 100 for easier identification and comparison.

More specifically, cylindrical cam member 120 is formed with an inclined slot 120^a in which a follower pin 121 is kept 30 in slidable engagement. Therefore, by turning the cam member 120 in one or another direction, the slide 114 will be shifted to-and-fro by the slidable engagement of the follower pin 121 with the cam slot 120^a. Thus, the same effect as before can be equally attained.

I claim:

1. A slide switch assembly with rotary spring detent mechanism, comprising a stationary metallic casing having substantially an elongated box shape opening downwards, a closure strip member made of an insulating material and closing physically the open bottom of said casing, a number of spaced stationary male contacts mounted on said closure member, a slide made of an insulating material and carrying thereon a plurality of movable female contacts mounted resiliently but fixedly on said slide, a return spring inserted 40 under compression between said slide and said casing, a stationary mounting member fixedly attached to one end of said casing, a manually rotatable shaft, a cylindrical cam member rigidly connected with said shaft, a detent means mounted on said cam member, a female camming groove or recess formed 45 on said cam member, and a male follower member formed on said slide and kept in cooperative engagement with said female camming means.
